UNITED STATES PATENT OFFICE.

MORIZ WEINRICH, OF YONKERS, NEW YORK.

APPARATUS FOR DRYING BONE-BLACK.

1,121,429.

Specification of Letters Patent.

Patented Dec. 15, 1914.

Application filed October 30, 1911, Serial No. 657,465. Renewed May 4, 1914. Serial No. 836,354.

To all whom it may concern:

Be it known that I, MORIZ WEINRICH, a citizen of the United States, residing at Yonkers, in the county of Westchester and State of New York, have invented certain new and useful Improvements in Apparatus for Drying Bone-Black, of which the following is a specification.

This invention relates to certain new and useful improvements in apparatus for drying, for revivifying, and for decarbonizing bone black; and for drying other granular or finely divided material as sugar, brewer's grain, etc.

15 The present improvements consist in certain new constructions and arrangements relating to the interior and the head-end piece of the revolvable drum in which the bone-black is heated and exposed to a draft of 20 air for removing through oxidation, impurities taken up during the use of said bone-black, and also any excess of carbon, as I will hereinafter describe and claim.

The object of the present improvement is 25 to greatly increase the capacity of the revolvable drum in which the bone black is heated, without increasing the amount of fuel, the temperature of the bone-black, while in the drum, being maintained more 30 uniform and at a lower level and better and uniform results obtained than by the use of apparatus at present employed for the purpose.

In my former Patent No. 586,278, dated 35 July 13/97, I describe a process for revivifying and decarbonizing bone-black; in my former Patent No. 769,421, dated September 6/04, I have disclosed one type of apparatus for operating the process of the first mentioned patent.

Heretofore, my decarbonizing drums, when constructed as a smooth cylinder of say 54 inches in diameter have been equipped with lifting blades or flights having a width of 45 about six inches, these blades or flights being curved at the inner edges and set against the drum at an angle of about 105°. This arrangement generally gave good results, but some of the bone-black retained by the 50 curved edges, was lifted too high and when falling in a hot state through the current of air maintained in the drum was very liable to kindle. Besides, the six-inch blades referred to did not hold much char, so that 55 the amount of char being in the drum was

not very great and its temperature accordingly could not be kept very uniform.

By the arrangement shown in the accompanying drawings and which illustrate my new arrangement of the interior of the drum, 60 the heated char will be exposed in a great number of thin streams to the draft of air which passes through the drum, whereby the oxidation of the impurities, or of any excess of carbon, will take place much more rapidly. 65 At the same time, owing to the much wider lifting blades or flights employed in the present instance, the amount of char kept in the drum is much greater than heretofore, so that its temperature can be maintained more uniform at the desired degree 70 insuring more uniform and better results.

In the accompanying drawings forming part of this specification and in which similar reference characters indicate like parts 75 in the several views, Figure 1 is a cross sectional view of a drum employing the salient features of my present invention. Fig. 2 is a plan view of a part of a lifting blade or flight showing three rows of slits. Fig. 2a is 80 a plan view of a part of a lifting blade showing slits of increased width. Fig. 3 is an end view of the head piece at the discharge end of the drum showing a plurality of discharge doors. Fig. 4 is a cross sectional 85 view of a drum showing blades or flights of slightly modified form, and arranged for the drying of granulated sugar, or other finely divided materials. Fig. 5 is a detail showing one of the discharge doors in the 90 head piece at the discharge end of the drum. Fig. 6 is a sectional view on the line 5—5 of Fig. 5. Fig. 7 is a horizontal sectional view of one end of the drum showing a part of the lifting blades and one of the discharge openings, and a closure therefor. Fig. 8 is a cross section of a part of the drum showing one type of knocker. 95

In the said drawings the drum, A, may be of any suitable character adapted to hold 100 the bone-black to be heated, said drum having any desired capacity and having secured around its inner periphery angle-iron or other brackets, b, b', b², b³, etc., which in practice will extend the whole length of the 105 interior of the drum, said brackets being riveted or otherwise firmly secured to the inner circumference of the drum and being spaced suitable distances apart. To these brackets are riveted or otherwise firmly se- 110

cured the lifting blades or flights a , a' , a^2 , a^3 , etc., these blades being shown in Fig. 1 as projecting radially inward from the inner circumference of the drum, and said blades, 5 in practice having a width of from 25% to 20% of the diameter of the drum, and when designed for lifting bone-black should be straight and without curvature at the inner edges.

10 By reference to Fig. 2 it will be seen that the inner portions of the blades are provided with a plurality of rows of narrow slits, c , c' , c^2 . There may be any desired number of rows of these slits; the slits run along the 15 whole length of each blade, with narrow integral or unbroken portions between the slits of the same row. For treating ordinary sugar refinery bone-black, the slits may have a width of from $\frac{1}{16}$ to $\frac{1}{4}$ of an inch; 20 for coarser bone-black they should be comparatively wider.

From this description it will be apparent that when the drum is slowly revolving the char will drop in a number of thin streams 25 through the draft of air maintained in the drum substantially as disclosed in my aforesaid prior patents; by opening the air vents in the hood covering the discharge end of the drum, as shown in my prior Patent No. 30 769,421, only on that side on which the char is lifted and dropped, most of the oxygen of the air admitted may be utilized, thus preventing any unnecessary cooling of the char and insuring a material saving in fuel.

35 In my aforesaid Patent No. 769,421, in Fig. 6 thereof, I show an end view of the discharge end of the drum, consisting of a rim provided with a number of openings for the discharge of the treated bone-black. In 40 Fig. 3 of the present drawings, I have reduced these openings in the rim, D, to four in number and have provided these openings with lids or doors, d , d' , d^2 , and d^3 , said doors being hung on hinges, g , and secured 45 by suitable bolts, h , h' , for closing or opening said discharges. By pushing back the bolts the doors will swing freely on their hinges and the char accumulated in the inclined drum behind the rim will flow out 50 through the swinging doors at the bottom of the drum, and by closing said lids the char is retained in the drum until it overflows the rim. The object is to prolong, if desired, the treatment of the char in the 55 drum to a certain degree.

In using the apparatus for drying granulated sugar, brewer's grain, etc., the slotted lifting blades require a different arrangement from that used for treating char, because the object to be sought in drying the sugar, brewer's grain, etc., is to expose the material through the whole diameter of the drum to the draft of air in a great number of thin streams. Accordingly, as shown in 60 Fig. 4, the lifting blades, e , e' , e^2 and e^3 , are

disposed tangentially to the curvature of the drum, say at an angle approximately of from 70° to 110° respectively, the inner ends of said blades being curved as shown. It will readily be seen that in this arrangement 70 a much larger quantity of material than heretofore can be kept in the drum and that practically the whole drum through its entire length is filled with a great number of thin streams of material exposed to the air 75 draft through the drum.

In that portion of the drum in which the material is still quite damp, the slits in the lifting blades have to be correspondingly wide so that the passage is not obstructed. 80 For granulated sugar, for instance, which is apt to form lumps, the slits in the feed end of the drum should be from 1 to $1\frac{1}{2}$ inches wide, gradually narrowing down toward the discharge end where the slits should be 85 from $\frac{1}{2}$ to $\frac{1}{4}$ inch. In such drums for simply drying granulated sugar or similar material the lifting blades should have a width of only 90 20% of the diameter of the drum, thereby giving the material a higher fall 95 through the current of air.

The passage of the damp material through the slits can be facilitated in any suitable manner as by placing any suitable knocker on top of the drum. 95

In view of the foregoing explanation it will be apparent that with the described lifting blades or flights the capacity of the drum can be either considerably increased without increasing the amount of fuel or the 100 temperature of the air current correspondingly lowered, thus simplifying and cheapening the final product.

A suitable form of knocker for facilitating the passage of damp material through the slits in the lifting blades is shown in Fig. 8, wherein is illustrated a part of the cross section of the drum, said drum having on its periphery suitable lugs, I , I' , I^2 and I^3 , etc., which operate under a suitable 110 knocker, K , on a rod or stem, which is pivotally secured at one end. The lugs act as cams to lift the knocker, and the same falls after escaping the cam and thereby imparts the desired knocking motion to the drum for 115 the purpose stated.

In Fig. 7 I illustrate a part of the drum in longitudinal section and one of the angle irons for supporting the fixed slotted lifting blades or flights, said drum having the rim, D, and said figure showing one of the discharge openings with its lid, d , depending from the hinge, g , and secured by the bolts, h , as before described. 120

Having thus described my invention what I claim as new and desire to secure by Letters Patent is:

1. In a revoluble drum for drying, for revivifying, and for decarbonizing bone black and for treating other granular or finely di- 130

vided material, lifting blades or flights on the interior of the drum and provided near their edges with a plurality of slits through which the material to be treated 5 passes and is exposed to the air in a number of thin streams.

2. In a revoluble drum for drying, for revivifying and for decarbonizing bone-black or for drying other materials, a retaining 10 rim secured to the drum at the discharge end provided with a number of delivery openings and means by which said openings may be kept closed or open.
3. A revoluble drum for drying, for re-

vivifying and for decarbonizing bone black 15 or for treating other granular or finely divided material, said drum having its interior provided with lifting agencies which are slotted near their edges in the direction of their length to enable the material to pass 20 through them in a number of thin streams.

In testimony whereof I affix my signature in presence of two witnesses.

MORIZ WEINRICH.
